UNITED STATES PATENT OFFICE

150,662

DESIGN FOR A TABLE

Russell A. Thornquist, Grand Rapids, Mich., assignor to Extensole Corporation, Sparta, Mich., a corporation of Michigan

Application February 26, 1947, Serial No. 137,170

Term of patent 14 years

(Cl. D33—14)

To all whom it may concern:

Be it known that I, Russell A. Thornquist, a citizen of the United States, residing at Grand Rapids, in the county of Kent and State of Michigan, have invented a new, original, and ornamental Design for Table of which the following is a specification, reference being had to the accompanying drawing, forming part thereof.

Fig. 1 is a perspective view of a table showing the new design.

Fig. 2 is a side elevation of the same, and

Fig. 3 is an end elevation of the same.

I claim:

The ornamental design for a table, substantially as shown.

RUSSELL A. THORNQUIST.
